TYPE-WRITING MACHINE.

1,111,401.

Specification of Letters Patent. Patented Sept. 22, 1914.

Application filed December 20, 1909. Serial No. 534,048.

To all whom it may concern:

Be it known that I, WILLIAM J. NEIDIG, a citizen of the United States, residing at Madison, in the county of Dane, State of Wisconsin, have invented a certain new and useful Improvement in Type-Writing Machines, of which the following is a specification, reference being had therein to the accompanying drawings.

10 Certain principles and features of my invention as described herein are included within the generic invention which is described and claimed in Letters Patent No. 1,087,045, granted Feb. 10, 1914, upon my 15 co-pending application filed April 30, 1909, Serial No. 493,193.

My general invention supplies the operator of a typewriting machine with automatic indicating means, under the novel control of a typewriter-mechanism part used in the operation of typewriting, whereby without exercising preliminary care he is able to inform himself of the position of his advancing sheet either with respect to the first line 25 printed thereon or to some other point on the sheet. It also supplies him with additional or with substitute indicating means under the novel control of such a typewriter-mechanism part, whereby such types as may 30 be desired of signaling devices and of machine-lock devices may be employed to indicate the arrival of the sheet into a predetermined line position. The present branch or division of the invention supplies the operator with such indicating means. The embodiment thereof shown in the drawings employs an operative member that is actuated from the platen under the control of means operating in the lateral movement of 35 the carriage of the typewriter, and the use of said means as a controlling agent constitutes one of the leading features of the present invention.

Another of the leading features thereof 40 is the use of a special type of drive, namely, embracing a mutilated gear, for actuating the operative member.

Other features are as hereinafter described and claimed. The said features are 45 intended to be useful not only in the specific combinations shown and described herein,

but in other uses for similar sheet-indicating purposes.

In the drawings, Figure 1 is an end view of the preferable application of my principle as specifically shown herein; Fig. 2 is a cross-section on the line A-A Fig. 1 of the wheel 5 and its attached rotary parts as shown in Figs. 1 and 3, but enlarged, the said connected parts being turned into the best position for illustration; Fig. 3 is a front view of some of the parts shown in Fig. 1; Fig. 4 is a front view of a typical modification thereof; Fig. 5 is a plan view on an enlarged scale of the parts shown in Figs. 1 and 3, the bell and its hammer being in horizontal section; Fig. 6 is a detail view of the bell-hammer and associated parts; Fig. 7 is a detail view in section on line 7-7, of Fig. 6.

Similar symbols of reference refer to similar parts throughout the several drawings.

The form of embodiment of the invention which is more particularly illustrated herein comprises a rotary part connected more or less directly with the platen by means embracing a mutilated gear, indicating means controlled or operated by the rotary part, comprising a series of upward-counting indices, a series of downward-counting indices, a signaling means, and a means rendering the machine inoperative, one or all of which may be employed in actual practice; and means controlling the action of the mutilated gear, whereby it remains disconnected from the platen after passing out of connection therewith until the sheet becomes positioned, and then, from a constant starting or initial position, is made to connect therewith.

The preferable application of the principle underlying the invention is that shown in my Figs. 1, 3 and 5, in which the platen carriage frame 12, carried upon the main frame 41 of the typewriting machine in usual manner, has journaled in its ends the platen arbor 13, bearing the platen 10, which is connected with the usual line spacing mechanism, operated by the line space lever 51 in the well-known way. The paper table 100 for the support of the entering sheet is also shown. Both the paper table and the

line-space lever may be attached to the carriage frame 12 in any commonly used manner, as will be readily understood by those familiar with typewriting machines.

5 Taking now this already-provided structure as a basis, I place upon the platen arbor 13 outside the carriage frame 12 the toothed wheel 11, attaching the same fixedly thereon by means of the key 44. I next attach upon the end of the carriage-frame 12 the axle-pin 21, and place upon the pin the composite rotary part shown in cross-section in my Fig. 2, comprising the bushing 42, the rotary part 6^{b1} fixedly borne thereon, the 10 toothed wheel 5 rotatively adjustable upon the bushing and the said part 6^{b1}, and the two annular parts 6^{a1} and 6^{a2}, both attached to the toothed wheel 5 by means of the pins 43. The part 6^{a1} is supplied with interdental spaces or notches 61 on its inner face, to engage with the tooth 17 on the lever 18, which rocks upon the fulcrum 53 within a 15 recess 37 cut to receive it in the part 6^{b1}, the recess being rectangular in form, and of a width sufficient for the rocking play therein of the lever. This lever is held in position as shown by the spring 35, attached to the part 6^{b1} by the pin or screw 54; and when 20 in position it acts lockingly upon the part 6^{a1} so that the toothed wheel 5 and its attached parts cannot change their rotative position relatively to the part 6^{b1}, and it also acts bindingly upon the part 6^{a2} as regards any lateral movement. The part 6^{b1} has 25 upon it two projections, the one being the pin 20, stationed near the periphery as shown, and the other the end of the lever 18, stationed away from the periphery, or toward the axis. The toothed wheel 5 is supplied with 30 a projection, also, lettered 14, a working view of which is had in Fig. 3 (and Fig. 4); and its periphery is not continuous, but has a gap 75 in it, some of the teeth being cut away, the said toothed wheel being a mutilated gear. The carriage frame 12 has journaled upon it the rocking U-piece 80 by 35 means of the rock-shaft 81 as shown best in Fig. 5, the shaft extending inwardly toward the center of the platen, where it is supported 40 by the carriage frame extension 82 attached to the front rail of the said frame 12. This inner end of the shaft 81 bears the fixedly attached lever arm 83, the end of which becomes an axle having an axis at right angles 45 to the axis of the shaft 81 with which the lever rocks. Upon this axle I place the roller-wheel 85 as shown; and for a track for the wheel I attach to the main frame 41 of the machine the track 86 to extend from 50 end to end of the said main frame, that is to say, parallel with the platen and with the usual carriage tracks. The bed of the track bends upward at an operatively suitable point into the mound or rise 87, the slope of

which may be quite gradual, and then downward again to track level. The U-lever 80 upon the outer end of the shaft 81 is given its form in order to bring it into operative relations with the projection 14 upon the outer face of the toothed wheel 5. It likewise terminates in an axle or pin 79 having an axis at right angles to the shaft-axis, the said pin bearing a pawl or click 78 that rests against the wheel 5 in the path of the projection 14. I attach to the carriage frame 12 the frame extension 22 by means of the bolts 64, and from this I project into the path of the projection 14 the brake-shoe or friction-stop 15, using the pin 65 and the spring 66 to carry and position the same, 80 and the support 63 to coöperate therewith and steady the pin. I also station upon the carriage frame 12 the pointer or index-guide 34. The platen arbor 13 has the usual twirler or finger-wheel 60 on the end thereof. 85

The action of the structure thus far described is as follows: The sheet may be imaged as completed, and the toothed wheel 5 as being still in mesh with the toothed wheel 11, the broken peripheral portion 75 90 lying either backward or forward from the engaging point. The sheet will now be twirled out of the machine in the usual way, by turning the platen forward, and another sheet entered and advanced into a printing 95 position. This forward movement of the platen will have been communicated to the toothed wheel 5 through the action of the toothed wheel 11; but sooner or later the broken or toothless portion 75 of the periphery of the wheel 5 will have been 100 brought around into the position shown in Fig. 1, the wheels will have passed out of mesh, and the brake-shoe 15 will have brought the now disengaged wheel 5 to a 105 stop, by acting upon the projection 14. The first line will now be printed; and as it is not customary for good stenographers to run over upon a new sheet a short line at the 110 end of a paragraph, it will be a line of a fair length at least, and usually of a normal length. During the printing of this line the wheel 85 will have followed the bed of its track 86, and up the slight incline or mound-rise 87; and as the wheel is stationed at the 115 end of a lever-arm on the shaft 81, the shaft will be correspondingly rocked, and the U-lever 80 with it, thus pressing the end of the pawl 78 operatively against the projection 14. The wheel 5 will thereupon be turned 120 forward past the gap in its periphery and into mesh with the wheel 11. The spacing lever 51 will now be used to space the platen forward for the printing of the second line, and as the toothed wheel 5 is now in mesh 125 with the toothed wheel 11, it will thereafter turn synchronously with the platen during two revolutions of the platen more or less,

that is to say, until the broken-out peripheral portion 75 again comes around to the toothed wheel 11. If it be found desirable, the projection 14, which in one of its functions is a ratchet-tooth, may be multiplied on the wheel 5, that is to say, the wheel may be supplied with a series of two or three or more angular teeth adapted to engage with the pawl 78, so that the said wheel will not be thrown into mesh at the first stroke of the pawl, but will only be spaced forward after two or three strokes to its engaging position. The pawl is acted upon once at each passage of the wheel 85 over the track-
 15 rise 87—that is to say, twice for each printed line.

It will now be seen that I have described a means whereby the toothed wheel 5 with its attached parts is brought around always 20 to a stopping point that is constant, or practically so, namely, the point where the working portion of its periphery ceases to be acted upon by the driving periphery of wheel 11, because of the break 75 therein, 25 and a means then whereby, during the printing of the first line, or before the printing of the second, the said toothed wheel 5 is rotated forward into a renewed peripheral engagement with the wheel 11 by the action 30 of a part used in the regular operation of the typewriting machine, namely the action of the carriage frame 12 in moving forward or backward across the main frame 41 in the well-known way. Suppose now that I 35 supply the periphery of one of the locked-together parts 6^{a1} and 6^{a2} with indices, preferably numerals, using marks that will indicate the position of the current printing point relatively to the first line on the 40 sheet, and placing these indicating marks so as in each case to come opposite the index-guide or pointer 34. Thus I mark that point of part 6^{a1} that is so stationed at the completion of my first line with the numeral 45 1, using a 0 to indicate the stopping point immediately preceding, before the action of the pawl 78 upon the wheel 5 has spaced the periphery forward. The spacing lever 51 is now used in the usual way, advancing 50 the sheet into position for the printing of the second line. As the toothed wheel 5 is now in mesh engagement with the wheel 11, it also is advanced thereby, bringing a new point in the periphery of the combined parts 55 6^{a1} and 6^{a2} opposite the pointer 34. This I mark on the part 6^{a1}, and so on, as high as I wish to go, my wheel 5 and its attached parts sustaining now always a constant operative relation to the platen advancing 60 the sheet. Such a series of indices might take the form of the line-indicator or scale 6^a in my drawings.

In my illustrations I show a scale counting by the ordinary double-spaced line, and

marked only for the alternate lines. It 65 could obviously be marked to count by the single-spaced line just as well, or by the triple-spaced line, or using any other unit of indication, instead of the line-unit. Such a line-indicator so connected will indicate 70 automatically to the operator without preliminary thought or any computation on his part the position of his current line-position on the sheet, relatively to the first line printed. I use also a second series of indicating symbols, described as follows: Upon the periphery of the rotary part 6^{b1} are placed indicating marks, preferably numerals, arranged to count progressively downward, instead of upward, also by the 80 line unit. I show it marked to count by the double-spaced line; but it could just as well be marked to count by the single-spaced or the triple-spaced line. I show it marked only for the alternate lines, but there need 85 be no omissions. Its use is as follows: It will be borne in mind that the part 6^{b1} is rotatively adjustable to the toothed wheel 5 and its attached parts, as already described. Suppose now that I am printing 90 twenty-five lines upon my sheet, and wish to remove my sheet when the twenty-fifth line is completed; and suppose also that I am printing matter like tabular matter, that cannot well be divided, and wish to know 95 line by line how far distant my twenty-fifth or last line is, in order not to begin upon matter that will not go into the space I have left;—by bringing the numeral 25 of my indices 6^b, or the peripheral point midway between the numerals 26 and 24, opposite the numeral 1, or the peripheral point midway between the numerals 0 and 2, of my indices 6^a, and leaving it there, during the time that my indices 6^a are counting the 100 lines upward from 1 toward my twenty-fifth or last line, my other indices 6^b will be counting them downward, beginning with the numeral 25 and ending with the numeral 1, or their peripheral positions, as explained. I will thus be enabled to tell at a glance, without making any mental computations, just how much printing space I have left upon my printed page. Or, I could set the scale 6^b to tell the distance to 110 the extreme bottom edge of the sheet, instead of to the last line I intend to print, at my pleasure, by adding the depth in line units of the bottom margin.

Any mechanism having a mode of operation such as has been described,—that is to say, having an operative member that is first brought into a constant operative position, and then at an operative moment constant relatively to the printing or positioning of the first line given a movement 125 constant with that of the sheet,—can be made not only to indicate the relationship

of the current line position to the first or the last, but it can be made to operate and control means of attracting the operator's attention when a predetermined line position has been reached. Almost any kind of signaling apparatus can be used with my mechanism. In my drawings I show means of attracting the operator's attention through the striking of a bell, and means for then rendering the machine inoperative, in addition to the indicating means already described, both being operated and controlled by an operative member having such a mode of operation.

15 My bell signal is given by the following means: Upon the frame extension 22, attached to the end of the carriage frame 12 as already described, is the bell 27, the central pin 88 supplying the means of support therefor. That portion of the frame extension 22 extending downwardly from the bell bears the inwardly-projecting axle-pin 70, shown best in the sectional detail view, Fig. 7, upon which is stationed the oscillating arm 72 (see more particularly Fig. 6), only the lower portion of which is shown in Fig. 3, together with the hub 68 and the lever-arms 67 and 69, both of which are attached to the hub and rock therewith as a single piece. The arm 67 carries the outwardly-projecting pin 71, the said pin engaging upon the arm 72 when rocked in the one direction against it. The other arm 69 projects upwardly into the path of the pin 20 on the rotary part 6^{b1}. The arm 72 carries upon its upper end the bell-hammer 26, and near its axis-end the outwardly-projecting pin 74. A similar pin 74 is stationed upon the extension frame 22, the two being connected by the bow-spring 73 in such a manner that they are pressed toward one another, with the effect that the bell-hammer 26 is pressed toward the bell 27. When now it is time for the bell to be struck, the pin 20 breasts the lever 69, rocking it upon its axis together with the connected hub 68 and arm 67, and thereby through the pin 71 swinging back the bell-hammer 26 from the bell 27 against the action of the spring 73. The pin 20 in due time passes on, the lever 69 is released, and the bell is thereupon struck by the bell-hammer. Hub 68 and its arm 67 and lever 69 are caused to remain normally in their position shown in Figs. 1, 3 and 6, and are returned to such position after being partly turned by the action of pin 20 in passing the lever 69, by the action of an eccentric weight-portion 95.

60 The means whereby the machine is rendered inoperative are described thus: Upon the carriage frame 12 and projecting outwardly therefrom is the axle 7, bearing journaled thereon the elbow lever 1. The upper arm of this elbow-lever projects into

the path of the pin 20 on the part 6^{b1} before described, whereas its lower arm carries the pin 33. Between the two ends of the carriage frame 12 and journaled therein both at one end and the other is the rocking shaft 57, which has fixedly attached thereto at either end inside the frame-ends 12 the crank-levers 52. These levers 52 in turn carry attached fixedly upon them by the ends thereof the horizontal-bar 3, so that the bar 3 throughout its entire length will swing in an arc upon the shaft 57 its axis, the two lying parallel the one to the other. The shaft 57 bears also the fixedly attached crank-lever 55, but this outside the frame 12, connected with the elbow lever 1 before named by means of the pin 56 on the said crank-lever, the connecting-rod 53, and the pin 33. The elbow lever 1 and its connected parts may be so balanced as to come to the position of rest as shown. I now journal in the two ends of the main frame 41, by means of the axles 48 and the appropriate bearings therefor, the rocking gate 50, having attached thereto about centrally of its length the piece 47, provided with the pin 46, the said pin 46 when thus attached to the gate being in effect a crank-pin upon the same arbor therewith. From this pin 46 extends the connecting-rod 36 upwardly and rearwardly. I show it bent irregularly to avoid interferences with other parts of the machine. This rod terminates in the sleeve-bearing 2, fitted upon the parallel bar 3 in such a manner that the horizontal bar 3 can slide therethrough from end to end without great friction as the said bar moves back and forth with the carriage, the bearing 2 remaining in a stationary position the while, about midway between the ends of the main frame 41. The guide pieces 49 assist in holding the rod 36 and its bearing 2 against a transverse movement with the carriage. I show them attached to the stationary track 40, which is attached in turn at either end to the main frame 41, and forms practically a part thereof. When it is time for the machine to be rendered inoperative, the pin 20 presses upwardly against the lever 1, and the shaft 57 is thereupon rocked, together with its attached arms 52, thus lifting the horizontal bar 3, and through the connecting rod 36 and its sleeve-bearing 2 raising the gate 50 into a position approximately vertical. This gate is to be stationed as shown underneath the battery of levers connected operatively with the type-bar keys 59 and the space-key 39, the normal position of all of which may be indicated by that of the end lever, shown in dotted outline 38. Such an arrangement of key-operated levers is the one more commonly employed upon type-writing machines today and need not be further described. As will be seen, when the gate 50 is raised into its vertical position 130

underneath these several levers, it will no longer be possible to depress them in the usual manner, but they will be locked against the action of the keys 59 and 39, and the machine will no longer be operative. Other means acting to lock the keys 59 and 39 could of course be employed, and a means other than a key-locking means employed to render the machine inoperative.

- 10 I will now describe more particularly the use of my invention. Suppose I desire to print a page thirty-two double-spaced lines in length: I first unlock the rotary part 6^a from its connection with the toothed wheel 5 and its attached parts by operating the lever 18. This lever 18 may be so stationed that its projecting end will lie directly under the pointer 34 at the moment the pin 20 releases the bell-operating lever 69.
- 15 Bringing the lever 18 around under the pointer 34, I hold it there in its unlocked position, and turn the platen 10 until the indices 6^a pass under the pointer as far as the numeral 32. I then release the said lever, which forthwith locks the several rotary parts named to rotate as a unit. My signal bell will now always ring when the platen is spaced forward for the printing of the thirty-second line, and my machine 20 will always be rendered inoperative if the platen is then spaced forward for the printing of an additional line, the pin 20 acting first upon the lever 69, and then a line-space later upon the lever 1. If for any 25 reason I wish to add further matter to my page, I can always do so by turning my platen forward a line to release the lever 1, and then backward into the printing position. It will readily be seen that as my 30 lever 18 sustains a constant relation rotatively to the part 6^a, and consequently to the indices 6^b, the numeral *l* of the said indices 6^b may be positioned to lie immediately above the projecting end of the said 35 lever 18, and the other numerals in the series at peripheral points related thereto; in which case the bell would always ring when the numeral *l* of the indices 6^b came opposite the pointer 34. If therefore the signal- 40 ing means be adjusted to operate when required, the indices 6^b will always indicate coöperatively therewith the number of lines between the current line position on the sheet and the line-position at which the signal 45 is set to be given, whatever the current line position may be.
- 45 In my Fig. 4 I show a modification of my invention, for the purpose of showing that the toothed wheel 5 can be rotated around 50 into mesh by means of another part used in the usual operation of the typewriting machine, in this case the line-spacing lever 51, though almost any part used in the normal printing or positioning of the sheet 55 could be employed instead, or a part having
- no other use whatever. The line-spacing lever 51 is here shown as fixedly attached to the rock-shaft 77 journaled upon the carriage frame 12; and in addition to the usual line-spacing pawl and its operating lever, 70 the crank-lever 80', bearing the pin 79 and the pivoted pawl 78, is attached thereto. The wheel 5 passes out of mesh as before; and then, after the insertion of the new sheet, the first line is printed. The spacing 75 lever 51 is now used, and the pawl 78 is at once driven forwardly upon the projection 14, turning the wheel 5 into mesh. As the first part of such a spacing stroke is usually idle as far as its effect upon the platen is concerned, the wheel 5 will be in mesh before the platen begins its movement, and will then move forward therewith as before. I show more particularly the track-and-roller means of bringing around the 80 wheel 5, for the reason that in some typewriting machines the platen is not spaced forward by means of a lever 51.
- 85 It is to be noted that the pawl 78 will pick up the projection 14 at any point within its stroke, wherever that projection may chance to be, and carry it forward to the end of its stroke, that is to say, into a contact operative position. It will be perceived that I have therefore in this specification 90 disclosed two separate means of bringing an operative member into a constant operative position, the first being by means embracing a broken periphery, and the second, by means embracing a pawl and projection or 95 monotooth. I have shown these means as acting coöperatively, the one with the other; but in my co-pending application filed December 5, 1912, Serial No. 735,108, I show the principle of the one used and not that 100 of the other. A monotooth ratchet-wheel and pawl could be used to bring an operative member into a constant starting position from any of its several secondary positions.
- 105 The series of indices 6^a and 6^b are preferably carried upon a periphery as shown, but it is not in all cases essential that they should be peripheral. I show them as controlled or operated by a rotary part, but it is not in all cases essential that they should revolve upon an axis as shown, nor that the part controlling them should be rotary. Markings or symbols other than numerals 110 may be employed, and units other than the line unit. It is not essential that the precise means of adjustment between the part bearing the projection or monotooth 14 and the part bearing the pin 20 herein shown should be employed. The indices 6^a may 115 be used alone, without the indices 6^b, and the indices 6^b alone without the 6^a indices, or both series of indices may be omitted and the bell signal alone used, or the means rendering the machine inoperative alone, or 120
- 125
- 130

either it or the bell signal used alone with the two series of indices named, or with either of them. The invention is not restricted to the employment of the bell signal as an audible signal, nor to the locking means shown as a means of rendering the machine inoperative.

It is to be further noted that many methods of bringing an operative member into a constant initial or starting position are known and commonly used in other arts, almost any of which would be the equivalent of the means employed in my mechanism, and furthermore, that the means disclosed herein are capable of taking many forms.

The invention is not restricted to the use of friction means for checking the movement of the mutilated gear. Other means than the pawl means shown can also be employed for rotating the said wheel forward into re-engagement, some of which are specifically described by me in my applications filed December 5, 1912, aforesaid and December 16, 1909, Serial No. 533,355.

25 The stroke of the pawl 78 against the monoothooth projection 14, whereby the wheel 5 is rotated forward into engagement during the printing of the first line, or at a moment having a definite relation to the printing of the first line, is preferably given as shown; but it is to be noted that it could just as well be given by another part used in printing the first line, or in positioning the sheet before or after the said printing operation—

35 and I illustrate in Fig. 4 how the line-space-lever for instance may be used in this duty. The preferable form of my invention for machines having the line-space-lever conveniently stationed would be that shown in Fig. 4; but for those in which the line-space-lever is absent, that shown in Fig. 1 would be used.

40 My general invention has as its pith the fact that I show means whereby an operative part, preferably rotary, controlling an indicating or signaling means, is brought into a constant initial or starting position before or by the time the sheet is brought into a relatively constant line position, and then is given a movement constant with that of the sheet.

45 As more specifically disclosed in the present application, I show means whereby a rotary member is made to revolve with the platen through a toothed connection therewith, means whereby it is brought to a stop at a constant rotative point through a break in the connecting means, specifically a break in the toothed periphery of the gear wheel, 55 cooperating with a detaining means, specifically a friction-stop or brake, and means whereby it is then spaced forward into connection with the platen by the action of parts in the typewriting machine, specifically the action of a part stationed upon the

main frame upon a part stationed upon the carriage, the said parts acting specifically upon a reciprocating pawl and against a monoothooth projection in connection with the mutilated gear. It is to be noted in this connection that instead of connecting my rotary member with the platen as shown, and the platen in the common and well-known way with the line-space-lever, I might have connected my rotary member with the line-space-lever direct, using the ordinary pawl-and-ratchet mechanism commonly employed in typewriting machines to rotate the platen, omitting the platen connection; or I might have used a pawl-and-ratchet mechanism operated by the action of a part stationed on the main frame upon a part stationed on the carriage to rotate my rotary member, omitting not only the platen connection but the broken periphery. And other similar combinations of structure are possible.

50 The devices shown in the drawings and described herein have a number of general objects in common with those of certain co-pending applications for Letters Patent filed by me, and Letters Patent granted thereon, and to a certain extent utilize various principles and features which are common to the devices shown and described in the said applications. Some of the said common principles and features are claimed broadly in Letters Patent No. 1,087,045, granted upon my application of April 30, 1909, aforesaid, and in Letters Patent No. 1,053,924, granted upon my application filed December 16, 1909, Serial No. 533,355, and in my application filed December 17, 1909, Serial No. 533,725.

55 The present invention is distinguished by the characteristic features which are specified in the following claims.

Having thus clearly explained the nature and objects of my invention, and the manner of applying it, I claim as new and desire to secure by Letters Patent—

1. In a typewriting machine, in combination, a laterally movable carriage, sheet-advancing means thereon, an operative member actuated from said means, indicating means called into operation through said member, and means operating in the lateral movement of the carriage to control the actuation of said operative member from said sheet-advancing means.

2. In a typewriting machine, in combination, a laterally movable carriage, sheet-advancing means thereon, an operative member actuated from said means, indices called into operation through said member to indicate successive positions of the sheet, and means operating in the lateral movement of the carriage to control the actuation of said operative member from said sheet-advancing means.

3. In a typewriting machine, in combina-

- tion, a laterally movable carriage, sheet-advancing means thereon, an operative member actuated from said means, an audible signaling means called into operation 5 through said member, and means operating in the lateral movement of the carriage to control the actuation of said operative member from said sheet-advancing means.
4. In a typewriting machine, in combination, typewriter-mechanism parts including a laterally movable carriage having sheet-advancing means thereon, an operative member actuated from said sheet-advancing means, means called into operation through 10 15 said member for rendering one or more of said typewriter mechanism parts inoperative for use, and means operating in the lateral movement of the carriage to control the actuation of said operative member from said 20 sheet-advancing means.
5. In a typewriting machine, in combination, printing means, a lock for said printing means to render the same inoperative for use in printing, a laterally movable carriage, a platen on said carriage, an operative member actuated from said platen, means operating in the lateral movement of said carriage to control the actuation of said operative member from the platen, and a 25 30 universal connection between said lock and said operative member effective to operate said lock from said member in every working position of the carriage.
6. In a typewriting machine, in combination, the main frame, a carriage movable thereon, a platen on said carriage, a revolute member actuated from said platen, indicating means called into operation through said member, and coöperating parts, one 35 40 thereof on said carriage and one thereof on said main frame, said parts operating in the lateral movement of the carriage to control the actuation of the revolute member aforesaid.
- 45 7. In a typewriting machine, in combination, the main frame, a carriage movable thereon, a platen on said carriage, an index-carrier actuated from said platen to bring indices into indicating position, and coöperating parts, one thereof on said carriage and one thereof on the main frame, said parts operating in the lateral movement of the carriage to control the actuation of the said 50 55 index-carrier.
8. In a typewriting machine, in combination, a platen, a toothed wheel rotating in unison therewith, a coöperating mutilated gear, indicating means called into operation through said gear, and a part having also 60 a function in the typewriting operation connected to control the engagement of said toothed wheel with said gear.
9. In a typewriting machine, in combination, a platen, a wheel rotating in unison therewith, a coöperating mutilated wheel, 65
- an index-carrier actuated through said mutilated wheel to bring indices into indicating prominence, and a part having also a function in the typewriting operation connected to control the engagement of said mutilated 70 wheel and the first-named wheel.
10. In a typewriting machine, in combination, a platen, a toothed wheel rotating therewith, a coöperating mutilated gear, an audible signaling means called into operation through said gear, and a part having also a function in the typewriting operation connected to control the engagement of said gear and said toothed wheel. 75
11. In a typewriting machine, in combination, typewriter-mechanism parts including a platen, a toothed wheel rotating with said platen, a coöperating mutilated gear engaging with said toothed wheel under the control of a typewriter-mechanism part, and means called into operation through said gear for rendering one or more of said typewriter-mechanism parts inoperative for use. 80 85
12. In a typewriting machine, in combination, a laterally movable carriage, a platen on said carriage, a toothed wheel rotating with said platen, a coöperating mutilated gear, indicating means called into operation through said gear, and means operating in the lateral movement of the carriage to control the engagement of said gear and said toothed wheel. 90 95
13. In a typewriting machine, in combination, a laterally movable carriage, a platen thereon, a wheel rotating with said platen, a coöperating mutilated wheel, an index-carrier connected with said mutilated wheel, and means operating in the lateral movement of the carriage to control the engagement of said coöperating wheels. 100 105
14. In a typewriting machine, in combination, a platen, a toothed wheel rotating therewith, a coöperating mutilated gear having a projection connected therewith, indicating means called into operation through said gear, and a part having also a function in the typewriting operation connected to control the engagement of said gear and said toothed wheel, through said projection. 110
15. In a typewriting machine, in combination, a platen, a toothed wheel rotating in unison therewith, a coöperating mutilated gear, an index-carrier actuated through said gear, a projection in connection with said index-carrier and gear, and a part having also a function in the typewriting operation connected to control the engagement of said gear and said toothed wheel, through said projection. 115 120
16. In a typewriting machine, in combination, a platen, an operative member actuated from said platen, indicating means called into operation through said member, a friction device for detaining said member in starting position, and a part having 125 130

also a function in the typewriting operation connected to control the actuation of said member from the said starting position.

17. In a typewriting machine, in combination, a platen, a driver wheel rotating in unison therewith, a coöperating mutilated wheel, indicating means called into operation through said mutilated wheel, a detent for detaining said wheel in starting position, 10 and a part having also a function in the typewriting operation connected to control the actuation of said wheel from the said starting position.
18. In a typewriting machine, in combination, typewriter mechanism parts including sheet-advancing means, an operative member actuated from said sheet-advancing means, indicating means called into operation through said member, means for giving 15 said member a constant starting position, and means including a pawl-and-ratchet device for controlling the actuation of said operative member from said starting position, under the control of one of said typewriter mechanism parts.

19. In a typewriter machine, in combination, a platen, an operative member actuated from the platen, indicating means called into operation through said member,

and means including a pawl and monoothooth 30 for controlling the operation of said member from the platen.

20. In a typewriter machine, in combination, a platen, a toothed wheel rotating in unison therewith, a coöperating mutilated 35 gear, an operative member actuated through said gear, indicating means called into operation through said member, and means including a pawl for controlling the engagement of said mutilated gear and said toothed 40 wheel.

21. In a typewriting machine, in combination, a platen, an operative member, indicating means called into operation through said member, toothed devices between said 45 member and the platen, said devices constructed to permit detention of said member independently of the platen, and a part having also a function in the typewriting operation connected to control the actuation of 50 said member by said toothed devices.

In testimony whereof I affix my signature in presence of two witnesses.

WILLIAM J. NEIDIG.

Witnesses:

CHAS. F. RANDALL,
ALICE H. MORRISON.
